DESIGN FOR A MAIL RECEPTACLE OR SIMILAR ARTICLE

Thomas B. Owens, Cleveland, Ohio

Application May 1, 1945, Serial No. 119,341

Term of patent 7 years

(Cl. D74—9)

To all whom it may concern:

Be it known that I, Thomas B. Owens, a citizen of the United States, residing in Cleveland, in the county of Cuyahoga and State of Ohio, have invented a new, original, and ornamental Design for a Mail Receptacle or Similar Article, of which the following is a specification, reference being had to the accompanying drawing, forming part thereof.

I claim:

The ornamental design for a mail receptacle or similar article, substantially as shown.

THOMAS B. OWENS.
